UNITED STATES PATENT OFFICE.

WILLIAM O. WAYMAN, OF CHICAGO, ILLINOIS, ASSIGNOR TO THE ILLINOIS
MALLEABLE IRON COMPANY, OF SAME PLACE.

AUTOMATIC TANK.

SPECIFICATION forming part of Letters Patent No. 655,288, dated August 7, 1900.

Application filed June 19, 1899. Serial No. 721,022. (No model.)

To all whom it may concern:

Be it known that I, WILLIAM O. WAYMAN, residing at Chicago, county of Cook, and State of Illinois, have invented certain new and 5 useful Improvements in Automatic Tanks, of which the following is a specification.

My invention pertains to tanks by which an automatic periodical flushing is obtained; and the object thereof is to provide novel, 10 simple, and reliable means for performing such functions.

The novel and advantageous features in construction and operation of my device will be apparent from the description hereinafter 15 given.

In the drawings, Figure 1 is a sectional elevation of a portion of a tank or cistern with my device in position therein, the full lines representing the float while being filled with 20 water, but before submergence, and the dotted lines showing the position of the pan in emptying its contents after the starting of the siphon; and Fig. 2, an elevation of the movable parts immediately after the filling of the 25 float and during its descent in the tank when the valve is opened.

My device is placed in the usual tank 1, having a constantly-open supply pipe or faucet 2 for supplying water thereto. The 30 discharging device may be, if desired, a siphon comprising a casting or casing 3, provided with a vertical partition 4, dividing the interior of such casing into two vertical chambers or passages 5 and 6, communicating at 35 the top, as clearly illustrated in the drawings. The casing is secured in the bottom of the tank or box in any suitable manner, so that it communicates with the usual outlet or discharge pipe 7. The passage 5 is open at the 40 lower end to communicate with the tank near the bottom, while the passage 6 communicates with discharge-pipe 7 and has a branch pipe 8, which might be termed a "siphon-starting inlet." This inlet is governed by a valve 9, 45 arranged on the end of an arm or stem 10, pivoted to a bracket 11 on the casing. This arm has an end 12, projecting upwardly beyond said pivoted point, so as to be actuated by the trigger device about to be described.

50 If the valve 9 should by any means be opened even momentarily when the tank is

filled with water, the siphon would be started and the water would drain out through the siphon in the direction of the arrows. My design and purpose are to give an intermittent 55 actuation of the discharging device, which is here shown as a siphon, and a consequent periodical flushing, and to accomplish these results automatically. To this end the following means may be employed substantially as 60 shown: Upon a lug or bracket 3^a upon the side of the casing I pivot the end 13 of an upwardly and outwardly extending arm 14, which is preferably bifurcated at its end or provided thereat with a bifurcated extension. 65 Between the bifurcations or arms 15 is pivoted off the center an open pan or float 16, which is self-dumping and one of whose ends 17 extends obliquely upwardly and outwardly, so that all the water will drain out of the pan 70 after the device is operated. The arm 14 has a stop 18, which strikes the side of the casing to arrest further upward movement of the float. While I prefer to provide the stop upon the arm itself, it will be understood that the 75 stop may be fixed on the casing and be contacted by the arm, which construction is a mere reversal and equivalent of that shown. Upon the end 13 of arm 14 is pivoted a pawl 80 or dog 19, which is adapted to engage the projecting arm 12 of the valve-stem.

The operation is as follows: When the incoming water in the tank reaches the float, it will raise the same, the pan or float resting horizontally on the top of the water. The 85 float will continue to rise until arrested by stop 18, and the water continuing to enter the tank will overflow the float and fill the same. Fig. 1 shows the float in its highest position and being filled with water. The float will 90 then become submerged and the weight of the same and of the arm will cause it to descend. However, when the float ascended the pawl had climbed up the inner side of arm 12 and had dropped in front thereof when 95 the float reached its highest point. Then immediately upon the descent of the float the pawl 19 will force arm 12 to the right, (see drawings,) opening valve 9 and causing sufficient water to enter branch 8 to start the siphon through passages 5 and 6. The valve 100 9 is opened momentarily, as when the float

has descended farther the pawl 19 will pass behind arms 12 and allow the valve 9 to close. When the float has reached its lowest position, or approximately so, it will tilt and discharge 5 the contained water. Owing to the peculiar shape of the float a full discharge will occur without requiring the float to turn to a position at right angles to its supporting-arm. The siphon action continues, of course, until 10 approximately all the water in the tank is discharged. The above operation is repeated continuously and automatically. It will be understood that either or both ends of the float may be formed obliquely, although the 15 construction shown will be found preferable.

I do not intend to limit myself to any particular species of use of my invention, nor necessarily to siphon - provided tanks, and contemplate using the same wherever applicable. My devices are designed for and capable of automatically emptying fluids from tanks of every description and used for every 20 purpose.

Although I have described more or less precise forms and details of construction I do not intend to be understood as limiting myself thereto, as I contemplate changes in form, the proportion of parts, and the substitution of equivalents as circumstances may 25 suggest or render expedient, and without departing from the spirit of my invention.

I claim—

1. An automatic discharge device for tanks comprising, in connection with a tank, a valve- 35 governed discharge therefrom, a float actuating said valve and consisting of a pan adapted to tilt when filled and adapted to be filled with water over its edge, such pan being dumped by the gravity of its contained water 40 when the water in the tank is being discharged, and means for arresting the upward movement of the pan to cause it to fill when the water in the tank reaches a predetermined level.

45 2. An automatic discharge device for tanks, comprising, in connection with a tank, a valve-governed discharge therefrom, and means for operating such valve comprising a float consisting of a pan pivoted above and at one side 50 of its center of gravity and having its top longer than the bottom and that end inclined which is the farther removed from the pivotal point, and means for arresting the upward movement of the pan in the tank to cause the 55 pan to fill when the water therein reaches a predetermined level, such pan being dumped by the gravity of its contained water when the tank is being discharged.

3. An automatic discharge device for tanks 60 comprising, in combination with a tank, a valve-governed discharge therefrom, a float-actuated trigger mechanism for operating said valve, said float consisting of a pan adapted to tilt when filled and adapted to be filled 65 with water over its edge after arrest of its movement with inflowing water, and to actuate such trigger mechanism while descending in

a horizontal position after submergence, said pan being dumped by the gravity of its contained water after the water in the tank has 70 receded and ceased to support the pan, and means for arresting the upward movement of the pan.

4. An automatic siphon device for tanks comprising, in connection with a tank, a siphon in the tank, a siphon-starting inlet, a valve governing such inlet and having a stem, an open pan or float, a pivoted arm carrying such float and having a projection contacting the valve of said inlet and opening the same 80 when the float fills with water and descends, the valve of said inlet being adapted to close after the siphon is started and before the water is drained from the tank.

5. An automatic siphon device for tanks 85 comprising, in connection with a tank, a siphon therein, having a siphon-starting inlet adapted to close after the siphon is started but before the water is drained from the tank, a valve governing said inlet, an arm pivoted 90 in the tank, a float open only at its top and pivotally carried at one end of said arm, and a pawl upon the other end thereof adapted to engage the valve when the float is submerged and descends.

6. An automatic siphon device for tanks comprising, in connection with a tank, a siphon therein having a siphon-starting inlet, a valve governing said inlet adapted to close after the siphon is started but before the 100 water is drained from the tank, an arm pivoted in the tank, an open float carried by the arm, such arm having a pawl engaging the valve to open it when the float is submerged and descends and a stop for arresting the upward movement of the float and cause it to fill with water.

7. An automatic siphon device for tanks comprising, in connection with a tank, a siphon therein having a siphon-starting inlet, 110 a pivoted valve governing said inlet, a projecting stem for such valve, an open pan forming a float, and an arm pivoted in the tank and carrying the float at one end and a pivoted dog at the other end, the dog moving 115 said stem to open its valve when the float is submerged and descends.

8. An automatic siphon device for tanks comprising, in combination with a tank, a siphon therein connected with the tank discharge and having a siphon-starting inlet, a valve governing said inlet, a float consisting of a pan over whose top edge the water from the tank flows when the upward movement of the pan is arrested, such pan having an 120 end extending obliquely outwardly and upwardly, an arm pivoted in the tank and carrying the float at one end, and actuating the valve by its other end, such arm being pivotally connected to the pan off its center of 125 gravity and nearer that end opposite said oblique end, and means for arresting the upward movement of the pan.

9. An automatic siphon device for tanks

- comprising, in combination with a tank having a discharge, a siphon therein connected with such discharge and having a siphon-starting inlet, a valve governing said inlet, 5 an arm pivoted in the tank and in its movements momentarily opening the valve, a float consisting of a pan open at its top from end to end, with one end extending obliquely outwardly and upwardly, said pan being pivotally supported so as to tilt when filled, and to dump by the gravity of the water therein and to discharge from such oblique end and means for arresting the upward movement of the pan to cause the same to fill with water from the 15 tank.
10. An automatic siphon device for tanks, comprising, in combination with a tank, a siphon connected therein with the tank-discharge and having a siphon-starting inlet, a 20 valve governing said inlet, an arm pivoted in the tank and having one end bifurcated with its other end controlling said valve, a float consisting of an open pan over whose top edge the tank-water flows when the upward movement 25 of the pan is arrested, such pan being pivoted in said bifurcated end, off and above the center of gravity of the pan when filled with water and dumped by the gravity of its contained water and means for arresting the 30 upward movement of the float.
11. An automatic siphon device for tanks comprising, in combination with a tank, a casing 35 therein forming a siphon connected with the tank-discharge and having a siphon-starting inlet, a valve pivoted on such casing and governing said inlet, an open pan or float, and an arm pivoted upon the casing and carrying said pan at its outward end and having a pivoted dog at its other end engaging said valve. 40
12. An automatic siphon device for tanks comprising, in combination with a tank, a casing 3 connected therein with the tank outlet or discharge and forming a siphon having a siphon-starting inlet 8, a pivoted valve 9 governing such inlet and having a projection 12, an open pan or float 16, a pivoted arm 14 carrying the pan, and a dog 19 pivoted on the arm 14 and coöperating with projection 12. 45
13. An automatic siphon device for tanks comprising, in combination with a tank having an outlet or discharge, a casing 3 connected therein with the tank-discharge and forming a siphon having a siphon-starting inlet 8, a valve 9 governing such inlet and having a valve-stem 10 pivoted on said casing, such stem having a projection 12, an open pan or float 16, an arm 14 pivoted on the casing and carrying said pan, a dog 19 pivoted on said arm and a stop 18 for limiting the upward movement of said arm. 50
